UNITED STATES PATENT OFFICE.

EMMETT W. STULL, OF NORWOOD, OHIO, ASSIGNOR TO ALLIS-CHALMERS COMPANY, A CORPORATION OF NEW JERSEY, AND THE BULLOCK ELECTRIC MANUFACTURING COMPANY, A CORPORATION OF OHIO.

CONTROLLER.

No. 892,464.

Specification of Letters Patent.

Patented July 7, 1908.

Application filed June 30, 1906. Serial No. 834,133.

To all whom it may concern:

Be it known that I, EMMETT W. STULL, citizen of the United States, residing at Norwood, in the county of Hamilton and State of Ohio, have invented certain new and useful Improvements in Controllers, of which the following is a full, clear, and exact specification.

My invention relates to controllers for electric motors, and especially to arrangements for preventing flashing at the contacts of railway controllers.

It frequently happens, especially when the car is being "notched along", that dangerous arcing or flashing occurs at the controller contacts when the controller is moved to "off" position. Sometimes this arcing will burn out the controller and absolutely disable the car.

It is the object of my invention to entirely avoid flashing at the controller contacts and to break the motor circuit elsewhere.

In one aspect my invention comprises the combination with a motor controller, of a magnetically operated switch arranged to be opened when the controller is moved backward into its first operative position.

In a more specific aspect my invention comprises the combination of a motor controller, a magnetically operated switch biased toward closed position and normally locked in such position, a magnet which unlocks said switch when the controller is in its second operative position, and a second magnet which tends to open said switch when the controller is in the first operative position.

Other objects and features of my invention will appear hereinafter.

The single figure of the drawing shows diagrammatically one embodiment of my invention.

The controller shown in this figure may be of any desired type, but is here shown as a series-parallel controller for two electric motors A and B. The controller drum 15 has operative positions 1 to 13 inclusive and is provided with contact segments coöperating with stationary contact fingers 16 to 28 inclusive. As the controller is moved between positions 1 and 8, the resistance R in the motor circuit is varied with the motors connected in series. Between positions 8 and 9, the connections of the motors are changed from series to parallel. Between positions 9

and 13 the resistance R is varied with the 55 motors connected in parallel.

The contact finger 16 is connected to the movable member 29 of a magnetically operated switch S. The stationary member 30 of this switch is connected to the trolley or 60 other collecting device 31 through a blowout coil 32. The movable member 29 is pivoted at 38, is biased toward engagement with the stationary member 30 by a spring 33, and is normally locked in such position by a spring- 65 pressed latch 34. The latch 34 is moved to unlock the movable member 29 when a magnet 35 is energized, this magnet being connected in series between contact finger 18 and the resistance R. There is another magnet 70 36 of the solenoid type which is connected in series between contact finger 17 and resistance R. The solenoid 36 tends to open the switch S whenever it is energized, but can only do so if the movable member 29 of said 75 switch is not locked by the latch 34. The switch S is normally closed. A dash-pot or other time-limit device 37 retards the closing movement of said switch, but allows a free opening movement thereof. 80

The operation of my invention is as follows: When the controller is moved into its first operative position the motor circuit is completed from trolley 31, through blowout coil 32, switch S, contact finger 16, the 85 proper contacts of the controlling drum, contact finger 17, solenoid 36, the whole of resistance R, and the motors A and B to ground. In this position the solenoid 36 tends to open the switch S but is prevented 90 from doing so by the latch 34. When the controller is moved into its second operative position, the solenoid 36 and the lowest section of resistance R are shunted by the engagement of contact finger 18 and its co- 95 operating contact segment on the drum. This completes a circuit through magnet 35 which will move the latch 34 to unlock the movable member 29 of the switch S. However, the switch although unlocked does not 100 open, because the solenoid 36 is short-circuited at this time. The further forward movement of the controller deenergizes magnet 35 and varies the motor circuits in any desired manner, but this latter having nothing to do with my present invention will not be described in detail. When the controller in its backward movement reaches 105

position 2, the magnet 35 is energized to move latch 34 to unlock the movable member 29 of switch S. Upon further backward movement to position 1, the solenoid 36 is energized, and the switch now being unlocked, the movable member 29 thereof is moved by the solenoid 36 to open the motor circuit at the contacts 29 and 30. Any arcing which takes place at these contacts is extinguished by the blowout magnet 32. Upon the final backward movement of the controller to "off" position no arcing takes place at the controller contacts because the motor circuit is already broken. In order 15 to allow the motorman sufficient time to move the controller from first to "off" position, the closing movement of the switch S is retarded by the dash-pot 37, the opening movement of the switch being unretarded. 20 The switch at which the motor circuit is broken may be located at any desired place, but is preferably so located as to be out of sight of the passengers.

In some controllers, as in the one shown, 25 the motor circuit is broken as the controller moves between the last series and first parallel positions. As the motors usually have considerable counter-electromotive force at this time, thus greatly reducing the sparking 30 which would take place at the controller, it is generally unnecessary to provide for having the circuit broken elsewhere than at the controller contacts when this change is made. However, by a slight rearrangement of the 35 parts this can be done if desired.

Many modifications of the particular system of connections herein set forth may be made without departing from the spirit and scope of my invention, and all these obvious 40 modifications I aim to cover in the appended claims.

What I claim as new is:—

1. In combination, a motor controller, and a magnetically operated switch through 45 which the motor current is always supplied, said switch being so connected and arranged that it is opened when the controller is moved backward into its first operative position.
- 50 2. In combination, a motor controller, a magnetically operated switch, and connections between the switch and the controller so arranged that the switch is opened when the controller is moved backward to its first 55 operative position but is unmoved when the controller reaches such position in its forward movement.
- 60 3. In combination, a controller for electric motors, a normally closed switch in series with the controller, and a magnet arranged to open said switch when the controller in its backward movement reaches its first operative position.
- 65 4. In combination, a motor controller, a switch biased toward closed position and in

series with the controller, and a magnet for opening said switch when the controller is moved backward through its first operative position.

5. In combination, a motor controller, a switch normally locked in closed position, means for unlocking said switch when the controller is in its second operative position, and a magnet tending to open said switch when the controller is in its first operative 75 position.

6. In combination, a motor controller, a normally closed switch in series therewith, a magnet arranged to open said switch when the controller is moved backward through 80 its first operative position, and means tending to close said switch.

7. In combination, a motor controller, a normally closed switch in series therewith, a magnet arranged to open said switch when 85 the controller is moved backward through its first operative position, means tending to close said switch, and means for retarding such closing.

8. In combination, a motor controller, a normally closed switch in series therewith, a spring latch for normally locking said switch in closed position, a magnet energized when the controller is in its second operative position to release said latch, and a second magnet energized when the controller is in its 95 first operative position tending to open said switch.

9. In combination, a motor controller, a normally closed switch in series therewith, a spring latch for normally locking said switch in closed position, a magnet energized when the controller is in its second operative position to release said latch, and a second magnet energized when the controller is in its 100 first operative position tending to open said switch, said magnets being in series with the controller.

10. In combination, a motor controller, a normally closed switch in series therewith, a spring latch for normally locking said switch in closed position, a magnet energized when the controller is in its second operative position to release said latch, a second magnet energized when the controller is in its first 115 operative position tending to open said switch, and means tending to close said switch.

11. In combination, a motor controller, a normally closed switch in series therewith, a spring latch for normally locking said switch 120 in closed position, a magnet energized when the controller is in its second operative position to release said latch, a second magnet energized when the controller is in its first 125 operative position tending to open said switch, means tending to close said switch, and a dash-pot for retarding such closing.

12. In combination, a motor controller, an electrically operated switch biased to closed position and permanently in series with said 130

controller whenever the motor circuit is complete, and connections whereby said switch is opened when the controller reaches a predetermined position in its backward movement.

13. In combination, a motor controller, a normally closed switch in series therewith, means for locking said switch in closed position, a magnet which unlocks said switch when the controller is in a predetermined position, and a second magnet which tends to open said switch when the controller is in another predetermined position.

14. In combination, a motor controller, a switch in series therewith, and magnets arranged to open said switch when energized in a certain order, and connections to the controller whereby said magnets are energized

in said order during the movement of the controller in one direction, but in another order during the movement of a controller in the other direction.

15. In combination, a motor controller, an electrically operated switch through which the full motor current is supplied when the controller is in a certain operative position, and connections whereby the motor circuit is always made at the controller but is broken at the switch when the controller in its backward movement reaches such position.

In testimony whereof I affix my signature, in the presence of two witnesses.

EMMETT W. STULL.
